UNITED STATES PATENT OFFICE

150,758

DESIGN FOR A PACK FOR FRAGILE
ARTICLES

William J. De Reamer, Crown Point, Ind., assignor to Mapes Consolidated Manufacturing Company, Griffith, Ind., a corporation of Delaware

Application November 19, 1945, Serial No. 123,891

Term of patent 14 years

(Cl. D58—13)

To all whom it may concern:

Be it known that I, William J. De Reamer, a citizen of the United States and a resident of Crown Point, county of Lake, and State of Indiana, have invented a new, original, and ornamental Design for a Pack for Fragile Articles, of which the following is a specification, reference being had to the accompanying drawing, forming a part thereof, in which:

Fig. 1 is a perspective view of a pack for fragile articles when in a closed condition, showing my new design.

Fig. 2 is a top plan view of the same when in an open condition;

Fig. 3 is a view partly in side elevation and partly in longitudinal section thereof; and

Fig. 4 is a view in end elevation of the same.

I claim:

The ornamental design for a pack for fragile articles, substantially as shown.

WILLIAM J. DE REAMER.
